Morris Spiegel

INVENTOR

BY

Samuel S. Mandell

ATTORNEY

UNITED STATES PATENT OFFICE.

MORRIS SPIEGEL, OF CHICAGO, ILLINOIS, ASSIGNOR OF ONE-HALF TO MINNIE RIDGEWAY BISHOP, OF CHICAGO, ILLINOIS.

DESIGN FOR A BOOK-COVER, CALENDAR, OR SIMILAR ARTICLE.

53,382.

Specification for Design.

Patented May 27, 1919.

Application filed November 22, 1918. Serial No. 263,792. Term of patent 3½ years.

To all whom it may concern:

Be it known that I, MORRIS SPIEGEL, a citizen of the United States, residing at Chicago, in the county of Cook and State of Illinois, have invented a new, original, and ornamental Design for a Book-Cover, Calendar, or Similar Article, of which the following is a specification, reference being had to the accompanying drawing, forming a part thereof.

The figure is a plan view of a calendar cover showing my new design.

I claim:

The ornamental design for a book cover, calendar, or similar article as shown.

MORRIS SPIEGEL.
